UNITED STATES PATENT OFFICE.

WALTER W. FESSLER, OF NEW YORK, N. Y.

SLEEPING-CAR.

SPECIFICATION forming part of Letters Patent No. 310,809, dated January 13, 1885.

Application filed May 27, 1884. (No model.)

To all whom it may concern:

Be it known that I, WALTER W. FESSLER, of the city, county, and State of New York, have invented a new and useful Improved 5 Sleeping-Car-Berth Inclosure, of which the following is a specification.

This invention relates to sleeping and drawing room cars, and has for its object to provide a means by which the seats, after they 10 have been converted into berths, may be inclosed without the aid of curtains, which is now the prevailing custom.

In the accompanying drawings, forming part of this specification, Figure 1 represents 15 a vertical section of a sleeping-car equipped with my improved method of inclosure, showing one section, A, after it is made up and entirely inclosed, another section, B, partly inclosed, and another section, C, before it is 20 made up and as it would appear when in use as a drawing-room car. Fig. 2 represents a plan view, showing more accurately the manner in which my improved inclosure is folded.

My improvement consists, principally, in 25 joining together, either by means of hinges or otherwise, a number of narrow vertical pieces, as shown at *d* and *d'*, in such a manner as will admit of their being folded flat against each other in alternate directions, and so closely as 30 to reduce the whole inclosure into a small compact form, capable of being stored in the recesses *c* and *c'*, as shown at *c''*, Figs. 1 and 2.

The series of strips from *o* to *o'* represent the front side of one inclosed section, A, which 35 is joined together at *M* by the aid of any suitable fastening, which is located on the inside of the partition or inclosure and easy of access to the occupant of the berth.

As shown at *M*, Fig. 1, the vertical pieces 40 are divided so as to make the inclosure of the top and bottom berth entirely independent of each other. This method of inclosing a section or berth has many advantages over the ordinary curtain-inclosure, which is very ob- 45 jective, first, because the curtains leave the occupant partly if not entirely exposed; second, the curtains prevent any circulation of air, comparatively speaking, and thus the occu-

pant must either raise the window and sleep in a draft or suffer himself to close confinement and impure air; third, the curtains are very seldom renovated or cleaned, and thus the occupant of a berth is subject to contagious diseases.

My improved inclosure being made of either 55 wood or metal, or a combination of the same, is not open to any of the above objections, but, on the contrary, has many pleasant features. Certain portions or all of the vertical pieces in my improved inclosure can be made 60 of lattice-work, thus providing means of a complete circulation of air through the entire car. The occupant of the lower berth is not subjected to exposure or annoyance by the entrance or exit of the party occupying the upper berth. It gives absolute privacy, and is a 65 guard against loss of personal property. The vertical pieces can be provided with folding-hooks and other conveniences, such as cannot be enjoyed with the curtain-inclosure.

Having thus described my invention, what I claim, and desire to secure by Letters Patent, is—

1. A sleeping-car berth or section inclosure consisting of narrow vertical strips, made of 75 wood or any suitable material, and hinged together in such a manner as will permit of their being folded flat against each other in alternate directions, in order that the said inclosure may be compactly incased in the side of 80 the car, as described and specified.

2. An inclosure for sleeping-car berths, consisting of narrow vertical strips joined as described, and so arranged as to make the inclosure of the upper and lower berths entirely 85 independent of each other, as described, and for the purpose herein set forth.

In testimony that I claim the foregoing improved sleeping-car-berth inclosure I have hereunto set my hand this 24th day of May, 90 1884.

WALTER W. FESSLER.
